SUPPORT BRACKET

James B. Johnson, Urbana, Ohio, assignor to W. B. Marvin Manufacturing Company, a corporation of Ohio

Application October 21, 1955, Serial No. 541,974

4 Claims. (Cl. 248—215)

This invention relates to a support bracket. The invention relates more particularly to a support bracket for a ventilator fan assembly. The invention relates still more particularly to an easily attachable and detachable support bracket for a ventilator fan assembly for a casement type of window or the type of window in which the window projects outwardly to open.

Most ventilator fan assemblies are easily mounted in a conventional ventilator assembly in which a window is slidable within a frame member. In such an application, the slideable window or ventilator is opened to such an extent that the ventilator fan assembly may be disposed within the opening, the fan assembly being firmly retained between the ventilator and ventilator frame by a clamping action as the ventilator is closed as far as possible with the ventilator fan assembly disposed within the ventilator opening. However, in a casement type of ventilator or the ventilator which projects outwardly to open, it has heretofore been impossible or impractical to employ the use of a ventilator fan assembly adjacent or within the ventilator opening. This is due to the fact that the ventilator fan assembly cannot be properly clamped by a closing action of the projecting ventilator.

Hence, an object of this invention is to provide means by which a ventilator fan assembly can be easily and readily mounted in or adjacent an opening of a ventilator assembly in which the ventilator projects outwardly to open.

Another object of this invention is to provide a support bracket which is adapted for use with any one of a plurality of types of ventilator screen and frame assemblies.

Another object of this invention is to provide a bracket for the support of a ventilator fan assembly, which bracket is adapted for use with any conventional portable ventilator fan assembly.

Another object of this invention is to provide a support bracket for a ventilator fan assembly which bracket may be easily and readily attached to or detached from a ventilator.

Another object of the invention is to provide such a support bracket which can be used with any conventional ventilator assembly.

Another object of the invention is to provide a support bracket for a ventilator fan assembly which support bracket is light in weight, sturdy, and which may be built at relatively low cost.

Other objects and advantages reside in the construction of parts, the combination thereof and the mode of operation, as will become more apparent from the following description.

In the drawings, Figure 1 is a front elevation view showing a support bracket of this assembly attached to a ventilator assembly and supporting a ventilator fan assembly.

Figure 2 is a section view taken substantially on line 2—2 of Figure 1.

Figure 3 is an enlarged front elevational view of a

2

support bracket of this invention attached to a ventilator assembly and having a ventilator fan assembly carried thereby.

Figure 4 is a section view taken substantially on line 5 4—4 of Figure 3.

Referring to the drawing in detail, a support bracket 10 of this invention comprises a relatively thin body 11 having a vertical portion 12 and a horizontal portion 14 integrally attached one to the other. The body 11 is 10 provided with ribs 16 on the front surface thereof. The vertical portion 12 has a projection 18 horizontally attached thereto at the upper end thereof and extending therefrom. The projection 18 is provided with a downwardly extending flange 20 at the end thereof. Disposed 15 at the rearward side of the vertical portion 12 of the body 11 and in spaced relation therefrom is an abutment plate 24. The abutment plate 24 is attached to the vertical portion 12 by means of a leg portion 26 having a flange 28. The abutment plate 24 is also provided with a leg 20 30 parallel to the horizontal portion 14 and partially disposed at the lower side thereof. The flange 28 and the leg 30 may be attached to the portions 12 and 14 by any suitable means, preferably by welding or the like. The leg 30 extends slightly beyond the end of the horizontal portion 14 and is provided with a plurality of upwardly extending lugs 32 at the end thereof.

The abutment plate 24 is parallel to the flange 20 of the projection 18 and is in alignment therewith as clearly shown in Figure 4.

30 Figure 1 shows the portion of a projecting type of ventilator assembly 36 which may form part of the interior of a room. The ventilator assembly 36 has a ventilator frame 38 which carries a plurality of stationary glass window portions 40.

35 Also attached to the ventilator frame 38 is a conventional screen frame 42 which is secured to the ventilator frame 38 by any suitable means such as by means of a plurality of screws and washer units 44. The screen frame 42 is in abutting engagement with the ventilator 40 frame 38 in a conventional manner and carries a meshed screen 46. Within the screen frame 42 is fixedly attached a rod 48, as shown in Figure 4, which aids in retaining the screen 46.

45 The projection 18 at the upper end of the vertical portion 12 of the body 11 is adapted to engage the upper surface of the screen frame 42 and to rest thereupon. The central portion of the conventional screen frame 42 attached to a ventilator frame 38 may be slightly bent outwardly in order that the flange 20 of the projection 50 18 may be slidably disposed intermediate the screen frame 42 and the ventilator frame 38 as shown in Figure 4.

55 The abutment plate 24 engages the screen 46 for retaining the vertical portion 12 in spaced relation from the screen 46. A ventilator fan assembly 50 provided with one fan or a plurality of fans may be supported by the support bracket 10. Preferably the ventilator fan assembly 50 is provided with a plurality of apertures or slots 52 as shown in Figures 1 and 4. The lugs 32 of the support bracket 10 are adapted to fit into and pass 60 through the apertures or slots 52 for retaining the ventilator fan assembly 50.

65 The ventilator fan assembly 50 may be provided with a comparatively thin wall frame member 56 as shown in Figure 4 so that the thin wall frame member 56 may be disposed intermediate the horizontal portion 14 and the lugs 32 for retaining the ventilator fan assembly 50 in proper spaced relation from the screen 46, as shown in Figure 4. The fan assembly 50 may thus be supported adjacent the screen 46 and adjacent a ventilator opening 70 in a ventilator assembly.

The side of a ventilator fan assembly 50 which faces the screen 46 may be easily and readily reversed so that

air may be drawn into a room or forced from the room by reversal of the sides of the ventilator fan assembly. This reversal may be readily carried out by removing the fan assembly from the bracket in the manner as shown in Figure 4, reversing the sides of the fan assembly, and again hooking the fan assembly over the lugs 32 by means of the apertures 52 in the wall frame member 56 of the fan assembly 50.

It is thus understood that the support bracket of this invention provides means by which a ventilator fan assembly can be readily and easily attached in or adjacent the opening in any conventional ventilator assembly.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A bracket for supporting a ventilator fan assembly adjacent a ventilator provided with a ventilator frame, a screen frame attached to the ventilator frame, a screen held by the screen frame, the fan assembly having a support structure provided with a pair of apertures therein, the bracket comprising a body member having a first portion and a second portion, the portions being normal one to the other, the first portion having a projection at the end thereof normal thereto and extending in the opposite direction from the second portion, a flange extending from said projection and normal thereto, a broad area abutment plate, the abutment plate having two parallel legs, one leg being attached to the first portion of the body member at the side thereof opposite the second portion of the body member, the other leg of the abutment plate being attached to the second portion of the body member, the abutment plate being parallel to the first portion of the body member and in alignment with the flange extending from the projection thereof, the projection and the flange engaging the screen frame to support the bracket, the abutment plate engaging an area of the screen thus aligning the bracket, a pair of lug members extending from the leg of the abutment plate which is attached to the second portion, the lug members extending in the direction of the first portion of the body member and at the end of the second portion of the body member, the lug members fitting into the apertures of the fan assembly so that the fan assembly is carried by the second portion of the body member.

2. A support bracket comprising an L-shaped body member having portions normal one to the other, a projection extending from one of said portions substantially parallel to the other portion, a flange attached at the end of the projection and extending substantially parallel to the portion to which the projection is attached, a plate extending the width of the body and more than half the length thereof, the plate having a pair of legs normal thereto, one of the legs being attached to one of said portions of the body member, the other of said legs being attached to the other portion of the body member and extending therefrom, the plate being disposed in alignment with the flange, and a pair of lug members attached to the last said leg at the end thereof and normal thereto.

3. In a support structure for a ventilator fan assembly

having a frame with an aperture therein and removably attachable to a screen frame provided with a vertically disposed screen, the screen frame having a horizontal upper bar provided with a front surface and an upper surface and a back surface, a body member having a straight vertical portion and a horizontal portion, an inverted L-shape member attached to the vertical portion at the upper end thereof and extending therefrom, the upper end of the vertical portion engaging the front surface of the horizontal upper bar, the L-shape member having a portion engaging the upper surface of the horizontal upper bar of the frame, the L-shape member also having a downwardly extending back portion disposed in spaced relation from the body member and parallel to the vertical portion of the body member, the back portion being adjacent the back surface of the horizontal bar, a broad area abutment plate rigidly attached to the body member, the abutment plate being disposed in spaced relation from the vertical portion and in alignment with said back portion of the L-shape member, the L-shape member thus supporting the body member as the L-shape member engages the horizontal upper bar of the frame, the abutment plate engaging an area of the screen below the horizontal bar, thus maintaining the vertical portion of the body member in a vertical position, the horizontal portion extending through the aperture of the frame.

4. A support structure for a ventilator fan assembly having a frame with a pair of apertures therein and removably attachable to a screen frame provided with a vertically disposed screen, the screen frame having a horizontal upper bar provided with a front surface and an upper surface and a back surface, the combination comprising a body member having an elongate straight vertical portion and a plurality of horizontal portions, there being a lower horizontal portion at the lower end of the vertical portion and an upper horizontal portion at the upper end of the vertical portion, the upper and lower horizontal portions extending in opposite directions, a downwardly extending flange attached to the upper horizontal portion at the end thereof, the flange being adjacent the back surface of the upper bar of the frame while the upper horizontal portion rests upon the upper bar, there being a space between the horizontal bar and the vertical portion of the body member, a broad area abutment plate having a pair of legs normal thereto, one of the legs being attached to the vertical portion of the body member while the other leg is attached to the lower horizontal portion of the body member, the abutment plate being in spaced relation from the upper horizontal portion and in alignment with the flange of the upper horizontal portion, the abutment plate engaging an area of the screen below the horizontal bar thus maintaining the vertical portion of the body member in vertical position, the lower horizontal portion of the body member and the leg of the abutment plate which is attached thereto being inserted through an aperture of the frame during support thereof.
